VOLTAGE REGULATOR WITH TEMPERATURE COMPENSATION

George W. Speth, Cleveland, Ohio, assignor to
The Leece-Neville Company, Cleveland, Ohio, a
corporation of Ohio

Application April 29, 1935, Serial No. 18,833

16 Claims. (Cl. 200—87)

This invention relates to electromagnetic devices, and more particularly to a voltage regulator of the vibratory type.

It is an object of the present invention to provide novel temperature compensating means for an electromagnetic device of the type having a movable armature.

Another object of the present invention is to provide an improved regulator for generators, such as the generators of vehicle lighting and battery charging systems, having novel means for compensating for changes in the operating temperature of the device.

Another object of the invention is to provide an improved generator regulator of the type having a vibratory armature, wherein a shiftable mount is provided for the armature and temperature responsive means is arranged to act on the mount to vary the operation of the armature.

20 A further object of the invention is to provide an improved voltage regulator embodying a magnet having a yieldable frame and a movable armature mounted thereon, and wherein temperature responsive means is arranged to act on the yieldable frame to vary the action of the armature.

Still another object of this invention is to provide an improved voltage regulator embodying an electromagnet having a core and a yieldable frame part with an armature mounted thereon to extend into vibratory cooperation with the core, and wherein temperature responsive means is arranged to act on the yieldable frame to vary the position of the armature with respect to the core.

It is also an object of this invention to provide an improved voltage regulator embodying an electromagnet having a core and a yieldable frame part with an armature mounted thereon to extend adjacent the core and to be pressed against a contact element, and wherein temperature responsive means is arranged to act on the yieldable frame part to vary the position of the armature with respect to the contact element and core.

Other objects and advantages of this invention will be apparent from the following description when taken in conjunction with the accompanying drawing, wherein

50 Fig. 1 is a plan view of a voltage regulator embodying my invention;

Fig. 2 is an end view thereof, and

Fig. 3 is a partial sectional view taken as indicated by line 3—3 of Fig. 2.

55 Various types of electromagnetic regulating

devices have been used heretofore with generators for the purpose of maintaining the terminal voltage or load current at a substantially constant value regardless of changes in speed or load of the generator, and various devices of this kind have been used heretofore with the generators of vehicle lighting and battery charging systems. My invention has to do with means for compensating for changes in the operating temperature of electromagnetic devices, particularly generator regulating devices. By way of illustration the invention is herein shown and described as being embodied in a device for regulating the terminal voltage of a generator, but it should be understood that the invention may be embodied in various kinds of electromagnetic devices and regulators.

In the drawing I have shown my temperature compensating means embodied in a voltage regulator of the type having an electromagnet 10 and a vibratory armature 11. The electromagnet 10 may comprise a frame part 12, and a core 13 having a magnetizing coil or winding 14 thereon. The frame part 11 may be of U-like form having spaced arm portions 16 and 17, and a transverse connecting part 18. The core 13 may be connected to the transverse frame portion 18, and the core energizing winding 14 may be disposed within the opening of the U-like frame.

The armature 11 is mounted on one of the arms of the frame, in this instance, the arm 16, so as to extend adjacent the core 13. Any suitable operating connection may be provided between the armature and the frame which will permit vibratory movement of the armature relative to the core. In this instance I provide the armature with a spring plate 19 which is connected to the frame, as by means of the screws 20, and is adapted to be flexed during movement of the armature.

In this instance the armature 11 is provided with upper and lower contact elements 21 and 22, which cooperate respectively with upper and lower stationary contact elements 23 and 24. The stationary contact elements are carried respectively by brackets 25 and 26, which may be mounted upon the arm 17 of the magnet frame. The brackets 25 and 26 are insulated from each other and from the frame by insulating layers 27 and 28.

The armature of the present device is normally biased away from the core 13 by suitable means, such as the spring 29, which has one end thereof connected to the outer end 31 of the armature and its other end anchored to a bracket 32 pro-

jecting from the arm 16 of the frame. The spring 30 tends to press the contact 21 of the armature against the stationary upper contact 23. The tension of the spring 30 may be varied 5 as desired, by means of the adjusting nut 33 which cooperates with the threaded extension 34 of the spring and bears against the bracket 32. The extension 34 projects through an opening of the bracket 32, the opening being of a shape to 10 prevent rotation of the threaded extension when the nut 33 is rotated. The nut 33 is yieldably held in any desired position of adjustment by means of the spring detent 35 which cooperates with the knurled portion 36 of the nut.

15 For the purpose of understanding the present invention it is deemed unnecessary to explain the electric circuits which are controlled by the co-operating pairs of contacts 21, 23 and 22, 24. It is thought sufficient for the purpose of the 20 present invention to explain that the armature 11 responds to magnetization produced in the core and frame by the winding 14, and is vibrated rapidly by the action of the spring 30 in combination with variations in the strength of the flux 25 produced by the magnet winding. The contacts 21 and 23 are closed except when the magnetization is sufficient to move the armature 11 against the action of the spring 30, and while these contacts remain closed they short circuit a resistance 30 element 38. When the regulator is connected to a generator in a manner well understood in the art, the opening and closing of the contacts 21 and 23 intermittently connects the resistance 38 into, and short circuits the same out of, the field 35 circuit of the generator. The contacts 22 and 24 may or may not be provided, but when used may be arranged to control other energizing circuits for the field of the generator.

In accordance with the present invention the 40 magnet frame 12 is yieldable or at least the arm 16 thereof which supports the armature 11 is shiftable relative to the core 13 and the stationary contact 23. By causing the shifting or flexing of the arm 16 of the magnet frame, as will be 45 presently explained, the operating position or vibratory action of the armature is changed with respect to the core 13 and the stationary contact 23.

For shifting or flexing the arm 16 which 50 constitutes a mount for the movable armature 11, I provide the temperature responsive element 40. This element is arranged to act on the frame of the magnet to cause shifting of the arm 16 to produce the desired effect upon the armature 11. 55 In this instance I employ a temperature responsive element in the form of a flat bimetallic strip and arrange the same to act on some portion of the yieldable magnet frame, preferably on the transverse part 18, as shown in Fig. 3 of the drawing. When changes occur in the operating temperature of the device, as the result of the resistance heating of the magnet winding or other causes, the bimetallic element 40 tends to assume a bowed condition, and in so doing stresses the magnet frame to cause relative movement between the arms 16 and 17.

The thermo-metal strip 40 may be attached 70 to the magnet frame, or may be clamped between a portion of the magnet frame and adjacent structure, such as the support 42, to which the frame of the magnet is connected by the screws 43. In this instance the thermo-metal strip 40 is connected to the transverse portion 18 of the frame and is also clamped between such trans- 75 verse portion and an elevated part 44 of the sup-

port 42. The connection of the thermo-metal strip to the transverse part 18 may be made in any suitable way such as by means of rivets 45 extending through the frame and through the strip adjacent the ends of the latter. The thermo-metal strip 40 may be of any size, shape or thickness suitable to produce the desired flexing of the frame. For the purpose of maintaining the desired electric circuits, an insulating strip 46 may be disposed between the element 40 10 and the portion 44 of the support 42. For a similar reason the screws 43 may be arranged to extend through insulating sleeves and washers 47 and 48.

In the operation of the present device the armature 11 is vibrated to cause the contacts 21 and 22 to cooperate with the contacts 23 and 24. Should an increase occur in the operating temperature of the device such as by reason of the resistance heating of the winding 14, the ampere 20 turns of the winding decrease but the temperature responsive element 40 tends to assume a bowed condition and in so doing stresses the yieldable frame of the magnet to cause the arms 15 and 16 to be sprung or swung toward each other and 25 toward the core 13. This movement of the arm 16 causes the hinged end of the armature 11 to be shifted toward the core 13, thereby decreasing the tension of the spring 30 and reducing the pressure of the contact 21 against the contact 23. 30 This shifting of the arm 16 and the armature 11 also causes a reduction in the width of the air gap between the armature and core 13. The decreased air gap and the decreased pressure on the contact 23 enable the armature 11 to respond 35 more readily to the magnetization of the winding 14, and thus the reduction in the ampere turns of the magnet winding by reason of the temperature coefficient of resistance is offset by the shifting of the armature. The compensating 40 action just explained is effective in this manner, regardless of whether the armature is operating on the stationary contact 23 or the stationary contact 24, or is operating intermittently between 45 these contacts.

When a decrease occurs in the operating temperature of the regulator, the ampere turns of the winding 14 increase but at the same time the thermo-metal element 40 tends to bow in the reverse direction and thereby swings or flexes the arms 16 and 17 of the frame away from each other. This movement of the arm 16 also shifts the position of the armature relative to the core and the contacts 21 and 24, so that the air gap between the armature and core is increased and the pressure of the armature contact 21 against the stationary contact 23 is increased. The effect thus produced on the armature is to render the same less responsive to magnetization of the winding 14 and thus offset an increase in the 50 ampere turns of the winding resulting from a decrease in its resistance. 55

From the foregoing description and the accompanying drawing it will now be readily seen that I have provided a simple and efficient temperature compensating means which can be conveniently applied to a voltage regulator or to various other electromagnetic devices. My novel compensating means can be very economically applied to such devices because it involves only the application of a relatively inexpensive thermo-metal element to the frame of the magnet in a manner to cause flexing or shifting of the portion of the frame upon which the armature is mounted. 75

While I have illustrated and described my invention in a somewhat detailed manner, it should be understood, however, that I do not wish to be limited to the precise details of construction and arrangements of parts illustrated and described, but regard the invention as including such changes and modifications as do not constitute a departure from the spirit of the invention and the scope of the appended claims.

10 Having thus described my invention, I claim:

1. In an electromagnetic device the combination of a magnet having a core with an energizing winding thereon, an armature, a yieldable magnet frame mounting said armature to be vibrated by energization of the magnet core, and temperature responsive means acting on said yieldable frame to vary the position of the same relative to the core and to correspondingly vary the vibratory action of the armature.

20 2. In an electromagnetic device the combination of a magnet having a coil provided with a core, a frame part adjacent said magnet, a movable armature on said frame part extending in cooperating relation to said core, and temperature responsive means acting on said frame part to vary the operating position of the armature relative to the core.

30 3. In an electromagnetic device the combination of a magnet having a coil provided with a core, a frame part adjacent said magnet, an armature mounted on said frame part for vibratory movement and extending in cooperating relation to said core, a contact element against which said armature vibrately engages, and temperature responsive means acting on said frame part to vary the vibratory action of the armature relative to the core and contact element to compensate for changes in the operating temperature of the device.

40 4. In an electromagnetic device the combination of a magnet having a core with a winding thereon, an armature extending adjacent said core, a contact element, a yieldable magnet frame mounting said armature for movement relative to the core, a spring acting on the armature to press the same against said contact element, and temperature responsive means adapted to flex said magnet frame to vary the pressure of the armature against said contact.

50 5. In an electromagnetic device the combination of a magnet having a frame and a core with a winding thereon, said frame having a yieldable part, an armature mounted on said yieldable part and extending adjacent the core, a contact element, a spring acting on the armature to bias the same against said contact element, and temperature responsive means arranged to deflect said yieldable frame part in a direction to vary the pressure of the armature against said contact element.

60 6. In an electromagnetic device the combination of a magnet comprising a frame and a core with a winding thereon, an armature movably mounted on the frame and extending adjacent the core, a contact element, a spring acting on the armature and normally biasing the same away from the core and against said contact, and a temperature responsive element arranged to act on the frame to vary the pressure of the armature against said contact and the width of the air gap between the armature and core.

70 7. In an electromagnetic device the combination of a magnet having a core with a winding thereon and a frame part spaced from the core, an armature on said frame part extending ad-

jacent the core, said frame part being yieldable, and temperature responsive means adapted to cause flexing of the yieldable frame part.

8. In an electromagnetic device the combination of a magnet having a winding and spaced frame portions one of which constitutes a core for the winding, a movable armature on the other frame portion to extend adjacent the core, and temperature responsive means acting on one of the frame portions to vary the position of the armature relative to the core.

9. In an electromagnetic device the combination of a magnet having a winding and spaced frame parts one of which constitutes a core for the winding and the other of which is yieldable, an armature on the yieldable frame part extending adjacent the core, and temperature responsive means acting on the yieldable frame part.

10. In an electromagnetic device the combination of a yieldable frame having spaced arms and a transverse part connecting the same, a core between the arms and connected with said transverse part, an armature mounted on one of said arms and extending adjacent said core, and temperature responsive means acting on said frame to flex the same to thereby vary the operating position of said armature.

11. In an electromagnetic device the combination of a yieldable frame having spaced arms and a transverse part connecting the same, a core between the arms and connected with said transverse part, a vibratory armature mounted on one of said arms and extending adjacent said core, and temperature responsive means arranged to act on the transverse part of said frame to cause shifting of said one arm and thereby vary the vibratory action of the armature.

12. In an electromagnetic device the combination of a yieldable U-like frame having spaced arms and a transverse connecting part, a magnet core disposed in the opening of the frame and having a winding thereon, a movable armature mounted on one of said arms and extending across said core, a support, means connecting the transverse part of said frame with said support, and temperature responsive means between said support and transverse part adapted to cause variation in the spacing of said arms to thereby vary the operating position of the armature.

13. In an electromagnetic device the combination of an electromagnet having a yieldable frame and a core provided with a winding, a movable armature mounted on the frame and extending adjacent the core, and a temperature responsive element having spaced portions thereof anchored to said frame whereby temperature changes cause flexing of the frame.

14. In an electromagnetic device the combination of an electromagnet having a yieldable frame and a core provided with a winding, a movable armature mounted on the frame and extending adjacent the core, a support to which a portion of said frame is connected, and a temperature responsive element disposed between said frame portion and support and having spaced portions anchored to the frame whereby temperature changes cause flexing of the frame.

15. In an electromagnetic device the combination of a yieldable frame having spaced arms and a transverse part connecting the same, a magnet coil disposed between said arms, a contact carried on one of the arms, a vibratory armature mounted on the other arm and ex-

tending adjacent the coil and cooperating with said contact, and temperature responsive means arranged to act on the transverse part of said frame to cause relative shifting of said arms and variation in the cooperation of the armature with the contact in accordance with temperature changes.

16. In an electromagnetic device the combination of a yieldable U-like frame having spaced 10 arms and a transverse connecting part, a magnet

winding disposed in the opening of the frame, a contact element carried by one of said arms, a movable armature mounted on the other arm to be vibrated by said winding and cooperating with said contact, and temperature responsive 5 means adapted to act on said transverse frame part to cause variation in spacing of said arms and thereby vary the cooperation of said armature with said contact.

GEORGE W. SPETH. 10
